Fig. 3

To all whom it may concern:

Be it known that I, Lloyd E. Campbell, a citizen of the United States of America, resident of the city and county of San Francisco, State of California, have invented a new, original, and ornamental Design for a Shrine, of which the following is a specification, reference being made to the accompanying drawing forming a part thereof.

Fig. 1 is a top plan view of a shrine, showing my new design;

Fig. 2 is a front elevational view thereof; and

Fig. 3 is an end view thereof, both ends being the same, the back being without ornamentation.

I claim:

The ornamental design for a shrine, substantially as shown.
